J. H. GRAHAM.
WIRE SPOKE CONNECTION.
APPLICATION FILED MAR. 23, 1921.

Reissued May 24, 1921.

15,109.

UNITED STATES PATENT OFFICE.

JAMES H. GRAHAM, OF TORRINGTON, CONNECTICUT, ASSIGNOR, BY MESNE ASSIGNMENTS, TO THE TORRINGTON COMPANY, OF TORRINGTON, CONNECTICUT, A CORPORATION OF CONNECTICUT.

WIRE-SPOKE CONNECTION.

15,109.

Specification of Reissued Letters Patent. Reissued May 24, 1921.

Original No. 1,333,019, dated March 9, 1920, Serial No. 188,434, filed August 27, 1917. Application for reissue filed March 23, 1921. Serial No. 454,904.

To all whom it may concern:

Be it known that I, JAMES H. GRAHAM, a citizen of the United States, residing at Torrington, in the county of Litchfield, 5 State of Connecticut, have invented certain new and useful Improvements in Wire-Spoke Connections, of which the following is a description, reference being had to the accompanying drawing, and to the figures 10 of reference marked thereon.

My invention relates to improvements in wire spoke connections.

The object of my invention is to provide a strong and durable connection between the 15 spoke and hub or between the spoke and rim to prevent the endwise thrust on the spoke from wearing or cutting the same at the point of contact with the rim or hub and at the same time allowing for the 20 ready insertion of the spoke.

A still further object of my invention is to provide a cheap, simple and effective connection which can be applied without altering the general construction of the hub or 25 rim.

In the accompanying drawings:

Figure 1 is a perspective view of a portion of a wheel showing the connection between the spoke and hub.

30 Fig. 2 is an enlarged vertical sectional view of the connection.

In the usual spoke connection now used the hub is provided with an outwardly extending flange having transverse horizontal 35 openings therethrough, the walls of which are straight, and a countersunk portion in which the head of the spoke fits, preventing the spokes from pulling through the openings. The spoke on the outside of the 40 flange is bent at an angle and the endwise thrust on the spoke causes it to engage a very small portion of the wall of the opening and to also engage the sharp corner of the opening which cuts and wears away the 45 spoke at one point.

In my improved spoke connection, the hub 1 is preferably provided with lateral flanges 2, which flanges are formed with 50 projections or radially extending flanges 4 surrounding said openings 3 forming a larger bearing surface for the spoke as will be later described. As illustrated in the

cross sectional view (Fig. 2 of the drawings) the walls of these openings curve continuously in the arc of a circle and are disposed so that the openings taper progressively inwardly from the inner face of the hub to the outer face of the radially extending flange 4. Preferably these openings are substantially bell-shaped in cross section. 55 The outer edge of the flange is cut away or flares outwardly as indicated at 6 to dispense with any sharp cutting edge that might engage the spoke and cut or wear the same. The spoke 6^a is of the usual construction, having the enlarged portion 7 bent at an angle as indicated at 8, and the end beyond the same is provided with the gradually enlarged bevel-shaped portion 9, the walls of which are concaved and are the 60 size of and formed on the same arc of a circle as that of the openings in the hub flange. Thus the spoke has a large bearing surface closely fitting the wall of the 65 opening.

By this structure it will be seen that any endwise thrust of the spoke does not give a direct transverse movement of the spoke 70 against the wall of the opening but causes a slight rolling action, so that the wear is on a large surface and there are absolutely 75 no sharp corners for wearing of the spoke.

Having thus described the invention, what I claim as new and desire to secure 80 by Letters-Patent, is:—

1. A spoke connection comprising a hub having a lateral flange provided with a series of transversely projecting flanges thereon, said hub and flanges being provided with continuous openings, the walls 85 of which form arcs of circles, the outer edges of said flanges flaring outwardly, spokes fitting in said openings, said spokes being formed with bell-shaped heads, the walls of which are of substantially the size 90 and formed on the same arc of a circle as the openings in the hub and flange.

2. A spoke connection comprising a hub having a lateral flange provided with a series of transverse openings tapering progressively inwardly from the inner face of the hub to the outer face of the flange, a 100 spoke fitting in each opening, each of said spokes being shaped substantially similarly

to and making contact with the walls of the opening throughout its extent.

3. A spoke connection comprising a hub having a lateral flange provided with a series of transverse openings substantially bell-shaped in cross section, a spoke fitting in each opening, each of said spokes being

formed with an enlarged head, substantially bell-shaped in cross section whereby to prevent shearing or pulling out of said head 10 from said openings.

In testimony whereof I affix my signature.

JAMES H. GRAHAM.
